UNITED STATES PATENT OFFICE.

ADOLPH J. SOMMER, OF RITZVILLE, WASHINGTON.

DESIGN FOR AN AUTOMOBILE BOLT AND NUT BOX.

53,107.

Specification for Design.

Patented Mar. 18, 1919.

Application filed January 19, 1917. Serial No. 143,391. Term of patent 7 years.

To all whom it may concern:

Be it known that I, ADOLPH J. SOMMER, a citizen of the United States, residing at Ritzville, in the county of Adams and State of Washington, have invented a new, original, and ornamental Design for Ideal Automobile Bolt and Nut Boxes, of which the following is a specification, reference being had to the accompanying drawing, forming part thereof.

The figure is a perspective view of the ideal automobile bolt and nut box, showing my new design.

I claim:

The ornamental design for an ideal automobile bolt and nut box, as shown.

ADOLPH J. SOMMER.

Witnesses:

J. H. LANSING,
C. H. CLODIUS.
